UNITED STATES PATENT OFFICE

EDWARD E. HOLLISTER, OF QUINCY, ILLINOIS, ASSIGNOR TO HOLLISTER-WHITNEY COMPANY, OF QUINCY, ILLINOIS, A CORPORATION OF ILLINOIS

AUTOMOBILE LIFT.

Application filed April 30, 1931. Serial No. 534,060.

This invention relates to an equalizing head and a platform or frame structure thereon for supporting a motor car on a vertically rising plunger for servicing motor cars, trucks, and buses.

The complete lift is known as a free wheel lift. The car to be serviced is run over the lift and power is then applied to the lift. This causes it to rise and engage with the front and rear axles of the car.

The free wheel lift is very popular among tire selling concerns for the reason that all of the wheels are free for changing tires without the use of jacks or other elevating apparatus.

In practically all motor cars the distance from the front axle to the floor is not the same as the distance from the rear axle to the floor, and I have found that this difference in clearance amounts to as much as 3 to 3½ inches and possibly more in some cars.

It will be seen that in case the head and platform are attached rigidly to the plunger, a car on which the rear axle is 3 inches higher than the front axle will put an undue load on the front of the lift, which will cause the lift to either bind or to rise with considerable resistance. This is due to the leverage exerted by the weight of one end of the car through the long lever arm formed by the half-length of platform, tending to tilt the plunger in its fixed cylinder.

I have experienced the greatest trouble in lowering the lift. It may descend properly until the rear wheels meet the floor. The lift will then bind and it requires considerable power to cause it to go on down so that the car may be moved off.

An effort has been made to avoid the defects of the lift just mentioned by placing a plunger under each end of the platform that supports the car axles. Besides being more expensive, this arrangement is uncertain in its action on account of the difficulty of synchronizing the movements of the two plungers. Being directly under the axles, the plungers interfere with the movements of the workmen, since much of the driving gear mechanism is in the vicinity of the axles.

My improvement provides for an equaliz-

ing movement of the ends of the platform sufficient to permit the lift to descend with a practically uniform load at both front and rear. To this end I mount the platform structure upon the plunger in such a manner as to allow a limited tilting movement of the platform on the plunger.

My invention comprises a plunger head so shaped that the side bars of the platform may embrace it and rock up and down at the ends while the bars rest on the head.

My invention further consists in the combinations and details of construction herein-after described and claimed.

In the accompanying drawings,

Fig. 1 is a top plan view of my invention;

Fig. 2 is a side elevation thereof, the platform or supporting structure being shown in its normally horizontal position;

Fig. 3 is a side elevation of the same, the platform being tilted by reason of the resistance due to the weight of the front end of the car, when the rising platform encounters the front axle;

Fig. 4 is a plan of the central portion of the lift on an enlarged scale;

Fig. 5 is a section on the line 5—5, Fig. 4;

Fig. 6 is a side view of the plunger head, the side bars of the platform being shown in dotted lines, and

Fig. 7 is a section on the line 7—7, Fig. 6.

Like characters denote like points in all the views.

My invention consists broadly of a platform or supporting structure 10 mounted for a slight rocking movement upon the head 12 of the plunger 11. The supporting structure consists of a pair of side bars or rails 13 of sufficient length to span the distance between the axles of a large-size car. These bars are held apart by spacers 14 adjacent the head of the plunger and spacers 14' at the ends of the structure. These spacers are of proper length to bring the side bars under the axles of the car, while permitting the car to run over the platform without engaging the side bars against the hubs or any other parts of the car. The side bars 13 are held together by tie-rods 15, 15' passing through the spacers 14, 14'. The middle spacers 14 have a suit-

able clearance so that the side bars may rock up and down without binding on the head. At one end of the supporting structure or platform is a cradle 16 for contact with the rear axle, and at the front end are supports 17 for the front axle.

The plunger 11 slides in a suitable cylinder which may be completely or partially buried in the ground. Compressed air for lifting the plunger is admitted through the pipes 18 controlled by the valve 19. The head 12 consists of a collar 20 rigidly mounted upon the upper end of the plunger and a top 21 having an upper plane surface. Suitably spaced from the collar are two side bars or flanges 22. These bars are connected to the collar 20 by webs 23, 24. The two sides of the top 21 are recessed as shown at 25 in Figs. 5, 6 and 7. The recesses extend completely across the head and the bottoms of the recesses form bearing surfaces for the upper flanges of the side bars 13. These bearing surfaces slope outwardly and laterally as shown in Fig. 5. They also slope downward and longitudinally 25 with respect to the side bars as shown in Fig. 6, forming very flat obtuse angles with each other so that the side bar flanges normally rest upon the apices of the angles and may rock in either direction when tilted by the 30 weight of the forward end of a car. Flanges 22 have tapering lower edges also as shown in Fig. 6. When the parts are assembled, the head is embraced by the inner flanges and the inner sides of the webs of the side bars. 35 Longitudinal movement of the supporting structure or platform on the head is prevented by the spacers 14. By this arrangement the platform is securely mounted upon the head and the construction of the head permits limited 40 rocking movement of the platform. When the end of the platform has been lowered approximately 3 or 4 inches, the upper flanges 13 rest upon the bottom walls of recesses 25 at one side of the center of the head and the platform is held against further 45 tilting by the engagement of the lower flanges against the inclined lower edges of the flanges 22 on the other side of the axis of the head.

The operation of my improved lift is as 50 follows:

Normally the plunger is in its lowermost position with the platform or supporting structure balanced on the apices of the inclined surfaces at the side edges of the head. 55 When it is desired to elevate a car for inspection, repairs, or for changing tires or wheels, the car is driven over the lift until its front axle is over the supports 17 and the rear axle is above the cradle 16. The plunger is now 60 elevated, lifting the structure until the supports 17 engage the front axle. Continued movement of the lift causes the platform to tilt on the head 12 without raising the front end of the car, until the cradle 16 engages the 65 rear axle. Both ends of the platform now

move upward, carrying the entire car. Should the weight at either end of the platform or supporting structure predominate, the tilting movement is limited by the impingement of the flanges of the side bars against the diagonally opposite upper and lower inclined surfaces of the head. When the car is elevated a suitable distance, further movement of the lift is stopped by cutting off the air supply through the valve 19. The lift is lowered, carrying the car with it, by opening the pipes 18 to the atmosphere and permitting the air to escape. These movements take place without binding or sticking at any point. When the rear wheel touches the floor, the lift continues to descend freely, and when sufficiently lowered it is disengaged from the front axle. The lift then descends to its lowermost position and the car is driven off.

My invention is not limited to the details of construction herein disclosed, equivalent devices being included within the scope of my invention.

The term "rocker bearing" includes any 90 form of bearing or pivotal connection that permits the platform to swing in the manner described.

What I claim is:

The combination with an elongated structure for lifting motor vehicles through contact with their axles, said structure having inwardly channeled portions near its middle, of a plunger having a head received in the channels, the upper and lower surfaces of said 100 head being tapered to permit limited rocking movement of the structure.

In testimony whereof I have hereunto set my hand.

EDWARD E. HOLLISTER.
